C. W. BARNABY,
TYPE WRITER PLATEN.
APPLICATION FILED SEPT. 23, 1913.

1,186,268.

Patented June 6, 1916.

UNITED STATES PATENT OFFICE.

CHARLES W. BARNABY, OF NEW YORK, N. Y.

TYPE-WRITER PLATEN.

1,186,268.

Specification of Letters Patent. Patented June 6, 1916.

Application filed September 23, 1913. Serial No. 791,335.

To all whom it may concern:

Be it known that I, CHARLES W. BARNABY, a citizen of the United States, residing in the borough of Richmond, county of Richmond, city of New York, and State of New York, have invented certain new and useful Improvements in Type-Writer Platens, of which the following is a full and clear specification.

10 This invention relates to mounts and driving connections for typewriter platens and has for its primary object to provide a mount of improved construction which will permit the employment of a platen which 15 does not limit the width of the sheet upon which the writing is to be recorded.

Another object is to provide an improved mount of this character which will permit a ready exchange of platens or if desired, 20 permit of mailing tubes and other cylindrical bodies being installed in lieu of the regular platen, thus making it possible to write directly upon an article of this character.

Another object is to provide an improved 25 hand operated connection, including a handle which is adjustable laterally to make it readily accessible for sheets of various sizes.

Other and further objects will appear in the specification and be pointed out in the 30 appended claims.

The preferred embodiment of my invention is shown on the accompanying drawings, in which,

Figure 1 is a rear elevation of a typewriter carriage which is provided with my improved platen mount and platen operating connections. Fig. 2 is an end elevation of the same taken from the right of Fig. 1, with the ratchet wheel removed. Fig. 3 is 40 an end elevation of another embodiment taken from the left end of Fig. 4. Fig. 4 is a front elevation of this embodiment. Fig. 5 is another end elevation of the same taken from the right end of Fig. 4.

45 In the embodiment of my invention shown on the drawings, the carriage frame comprises a plurality of longitudinal members 1 and 2 and a pair of laterally spaced end frames 3 which are rigidly secured to said 50 longitudinal members. The member 1 is provided with a roller 4 journaled on the screw 5. A rack bar 6 is also rigidly secured to the end frames 3 and constitutes one of the longitudinal members of the carriage frame. Journaled within the end frames 3 are a plurality of rollers 7 and 8, the former

being disposed to the rear and the latter to the front of a cylindrical body or platen 9, said body or platen being in this manner peripherally supported and adapted to be 60 rotated on its axis 10. Such body may be a mailing tube or any other similarly formed body upon which it is desired to imprint a record of any kind. Suitable and efficient means for retaining the body or platen 9 in 65 position upon the rollers 7 and 8, are provided by the pressure rollers 11. According to the present embodiment of my invention, two of these rollers which are preferably disposed adjacent the ends of the platen or 70 cylindrical body 9, are journaled upon pins 12 which are carried by the forked upper ends of resilient arms 13, the lower ends of said arms being rigidly secured to laterally projecting branches of the end frames 3. 75 There is thus provided a resilient pressure tending to maintain the body or platen 9 in suitable position to be printed upon while at the same time maintaining the required degree of pressure between said body or 80 platen 9 and the supporting rollers 7 and 8. As shown in Figs. 2 and 3, the rollers 7 and 8 are provided with end journals 14 by means of which they are rotatably mounted in the end frames 3. Secured to the right 85 hand journals of the rollers 7 and 8, according to Fig. 1, are gears 15 and 16. The gear 15 intermeshes with a driving gear 17 which as shown in Fig. 1, is keyed to a hollow shaft 18 which is journaled at opposite ends 90 within the end frames 3. Also keyed to the hollow shaft 18 is a ratchet wheel 19 which is adapted to be rotated by any suitable line-spacing mechanism (not shown on the drawings). Extending longitudinally of the hollow shaft 18 is a slot 20 within which the pins or screws 21 are adapted to reciprocate as the extensible handle now to be described, is moved inwardly and outwardly. Said 95 handle comprises a rod 22 which telescopes 100 within the hollow shaft 18 and a hand or finger grip 23 which is secured to the rod 22. Slidably mounted on the hollow shaft 18 is a band or ring 24 which is rigidly connected to the rod 22 by means of the pins or screws 105 21. By this means, the hollow shaft 18 may be rotated by hand by gripping the hand or finger grip 23. As shown best in Fig. 2, power is transmitted from the gear 17 to the gear 16 on the rear platen roller 7, by means 110 of interposed idlers 25. According to the embodiment of my invention shown in Figs.

3, 4 and 5, a platen 26 is made open at one end and closed at the other. Thus the shaft 27 which supports the platen 26 at one end, is journaled in an end frame 28 and is provided with a ratchet wheel 29 and a hand grip 30. Secured to the end frame 28 is a resilient finger 31 which cooperates with another resilient finger 32, which is secured to the opposite end frame 33 in resiliently holding the platen 26 against the supporting rollers 7 and 8', which are journaled at opposite ends within the end frames 28 and 33. Said end frames are secured together by means of rack bar 34, tie bar 35 and longitudinal member 36, which carries the roller 37.

The advantages and method of manipulating my improved construction will now be readily understood and briefly referred to, are as follows: According to the embodiment shown in Figs. 1 and 2, end pivots and bearings are dispensed with entirely, the platen or other body which is suitable to be rotated by the supporting rollers 7 and 8 being centered and rotated by said rollers under the required degree of pressure for securing the best results in making a record thereon. Instead, therefore, of providing similar rolls for merely holding the paper to the platen, I employ these rollers to drive the platen and at the same time provide an open end platen which permits a sheet of indefinite width to be employed in the machine. In order to make the hand grip 23 on the hand operating feed rod 22, readily accessible for any width of paper which may be used, it is made extensible in the manner hereinabove pointed out, so that said hand grip can be made to project beyond the lateral edge of the sheet and thereby adapted to be operated without inconvenience. By means of this construction, that is by omitting the end pivots, bearings and handles, I can employ a platen or body of similar form of indefinite length. Or if desired, the extreme length of the platen and its housing can be reduced to a minimum to correspond to a minimum width of the main frame which will house a standard keyboard, thus making it possible to materially reduce the width of typewriting machines without any reduction in their capacity. A further advantage is that the platen is readily removed and replaced when desired, a very simple manipulation being required for this purpose. In this connection it will be seen that a simple and efficient means for replacing a platen at any time by one of softer or harder material, according to the requirements of various kinds of work, is provided. This construction is also convenient for the substitution of mailing tubes or for making a record upon long envelopes or other articles to be written upon which may extend any required amount beyond the confines of the

machine. In the embodiment shown in Figs. 3, 4 and 5, the overhang of the sheet or other body to be written upon is confined to one end of the platen instead of being arranged to overhang on both ends as is possible with the embodiment shown in Figs. 1 and 2. I do not specifically claim the embodiment shown in Figs. 3, 4 and 5 in the present application as such embodiment constitutes the subject matter of my division application executed May 3rd, 1916, filed May 5, 1916, and serially numbered 95,612.

Obviously, various modifications in the construction herein shown and described, could be embodied within the scope of my invention, so that I do not wish to be limited to the specific constructions shown and described.

What I claim is:

1. In a machine of the character described, a carriage provided with rolls journaled on fixed axes, the axes of said rolls being suitably arranged to center a platen or the like with respect to an axis about which said platen or the like is to rotate, a platen or the like journaled freely upon and supported entirely by said rolls and means for applying power to one of said rolls independently of said platen or the like for driving said platen or the like. 25

2. In a machine of the character described, a carriage provided with rolls suitably mounted to center a platen or the like with respect to an axis about which it is to rotate, a platen or the like freely journaled on and supported entirely by said rolls, and means connecting said rolls independently of said platen or the like for driving said rolls in unison. 100

3. In a machine of the character described, a carriage provided with rolls suitably mounted to center a platen or the like with respect to an axis about which it is to rotate, a platen or the like freely journaled on and supported entirely by said rolls, and means connecting said rolls independently of said platen or the like for driving said rolls in unison, said rolls being journaled in bearings rigid on said carriage. 110

4. In a machine of the character described, a movable carriage, a platen or the like, rolls for carrying the entire weight of said platen or the like, said rolls being in peripheral running contact with said platen or the like, and bearings rigid with said carriage and within which said rolls are journaled, the axes of said rolls being arranged below the axis of rotation of said platen or the like. 115

5. In a machine of the character described, the combination with a carriage, of a platen, rolls journaled in said carriage and peripherally contacting with said platen to rotatably support it, and means for retaining said platen in position on said rolls said 120

rolls being geared together independently of said platen to move in unison for driving said platen.

6. In a typewriting machine, the combination with a movable carriage, of a platen, said carriage being suitably formed to permit a sheet of paper on said platen to overhang the carriage at either end, rolls journaled in said carriage on axes below the axis 10 of said platen, said platen being supported entirely by said rolls and in peripheral contact therewith, means for driving said rolls to rotate said platen, and a handle operably connected to said platen and adjustable 15 lengthwise thereof to accommodate paper of greater width than the length of said platen.

7. In a machine of the character described, the combination, with a carriage, of a platen, rolls journaled in said carriage below and peripherally contacting with said 20 platen, said rolls bearing the entire weight of said platen to adapt it to carry a sheet of greater width than the length of said platen, and a platen-rotating handle operably connected to said platen and adjustable 25 lengthwise thereof to extend outside of the lateral edge of said sheet.

CHARLES W. BARNABY.
